UNITED STATES PATENT OFFICE.

DAVID D. BUICK, OF DETROIT, MICHIGAN.

DESIGN FOR A WATER-CLOSET TANK.

SPECIFICATION forming part of Design No. 27,823, dated November 9, 1897.

Application filed August 2, 1897. Serial No. 646,823. Term of patent 14 years.

To all whom it may concern:

Be it known that I, DAVID D. BUICK, a citizen of the United States, residing at Detroit, in the county of Wayne and State of Michigan, have invented and produced a new and original Design for Water-Closet Tanks, of which the following is a specification, reference being had therein to the accompanying drawings.

10 Figure 1 is a perspective view showing a tank embodying my new design. Fig. 2 is a top plan thereof, and Fig. 3 is a side elevation thereof.

As shown in the drawings, the leading feature is a rectangular wall-plate with a rectangular tank springing centrally out therefrom.

15 C is a rectangular tank having the front and side vertical walls of substantially the

same height. The fourth or back side of the 20 tank, which constitutes the wall-plate A, is of greater dimensions than the other sides thereof, thus forming marginal faces E, exposed all around the tank proper, C, when viewed from the front. The plate A is also 25 rectangular and is formed with the rounded or curved corners B.

The vertical corners F and the lower corners of the tank C are rounded.

What I claim as my invention is—

30 The design for a water-closet tank as herein described and shown.

In testimony whereof I affix my signature in presence of two witnesses.

DAVID D. BUICK.
